UNITED STATES PATENT OFFICE.

DAVID LEVINSON, OF CHICAGO, ILLINOIS, ASSIGNOR TO WILSON-WESTERN SPORTING GOODS CO., OF CHICAGO, ILLINOIS, A CORPORATION OF ILLINOIS.

ATHLETIC GARMENT.

Application filed January 17, 1923. Serial No. 613,102.

To all whom it may concern:

Be it known that I, DAVID LEVINSON, a citizen of the United States, residing at Chicago, in the county of Cook and State of Illinois, have invented a certain new and useful Improvement in Athletic Garments, of which the following is a full, clear, concise, and exact description, reference being had to the accompanying drawings, forming a part of this specification.

The invention relates to athletic garments and particularly to means whereby certain relatively full portions of an athletic garment, such as foot-ball pants, may be arranged and held so that the full leg portions of the garment, when worn by a player, can not be readily grasped by an opponent to thereby interfere with and impede the actions of the player.

The invention has as its prime object the provision of a leg band which may be closely fitted relatively to the leg of a person, so that it will encircle the leg and, in addition, will permit the relatively full leg portions of the pants to be folded and arranged under the band so that the fullness will be inaccessible to an opponent and will not provide a means which may be grasped and held by him.

It is a further object of the invention to provide a leg band capable of performing the above named function, which is flexible and elastic and will yield and accommodate itself to the various movements of the leg during movement of the player and, in addition, which will permit of its adjustment so that it may be closely fitted to the leg with various degrees of tightness and snugness.

It is a further object of the invention to provide the leg band with means whereby it may be secured to the garment with which it is to be used, which means may be by lacing or otherwise fastening it thereto.

It is an additional object of the invention to provide a means whereby the leg band may be secured to the garment so that it will be held in associated relation with the garment when not performing the function of holding the excess material of the garment in the manner above explained.

The invention will be explained and more readily understood when read in conjunction with the accompanying drawings which illustrate various arrangements of which the

invention is susceptible, and it will be obvious that further changes and modifications may be made without departing from the spirit of the appended claim forming a part hereof.

In the drawings,

Figure 1 is a perspective view showing one form of the invention applied to foot-ball pants;

Figure 2 is an elevation of the leg band shown in Figure 1;

Figure 3 is an enlarged sectional view taken on line 3—3 of Figure 2;

Figure 4 is a sectional view taken on line 4—4 of Figure 1, except that the lacing is shown differently from the lacing in Figure 1;

Figure 5 is an elevation of a fragmentary portion of the parts shown in Figure 1, illustrating one of the means employed for securing the device to the pants;

Figure 6 is a section of a fragmentary portion of a leg band such as illustrated in Figure 1, showing a modified structure releasably securing the ends of the band together;

Figure 7 illustrates another modified arrangement which may be employed for holding the leg band with respect to the garment; and

Figure 8 is a section taken on line 8—8 of Fig. 7.

The invention is illustrated and will herein be explained as associated with foot-ball pants. It is obvious, however, that the invention is not limited in its use to foot-ball pants as it may be employed in connection with other forms of garments.

The foot-ball pants, illustrated in the drawings and generally designated 10, are provided with the thigh portions 11 and 12 and knee portions 13 and 14. The foot-ball pants illustrated are constructed with a plurality of stays or thigh guards 15, arranged parallel to each other, and secured to the thigh portions in the front of the garment. The stays, as shown, are covered and held in position by any suitable material and are used as a protection for the thighs.

The leg portions of foot-ball pants are usually more or less full, and, therefore, provide portions which may be readily grasped and held by an opposing player in order to hold, hinder, and stop the player in his progress during the playing of the game.

In the form illustrated, because of the employment of the thigh guards 15, the fullness will generally be in back of the leg portions of the garment (see Figure 4). As hereinbefore stated, it is an object of the invention to provide a means whereby this fullness of the pants leg may be rendered inaccessible to the opposing player and the legs of the pants be made so smooth and taut 10 by means of the invention that there will be no portion of the pants leg which may be effectively grasped or held by the opposing player.

As shown in Figure 1, leg bands 16, 17, 18, 15 and 19, of suitable shapes, are employed in conjunction with the pants legs, leg bands 16 and 17 being employed on the thigh portions, and leg bands 18 and 19 being employed on the knee portions. The leg bands 20 are made of any suitable flexible and elastic material, the object being to provide the necessary elasticity and to permit the required freedom of movement of the legs which are encircled and also to permit the 25 various adjustments of the leg bands which may be required by the player.

The construction of one leg band being substantially identical with that of the others, an explanation of the construction and 30 application of the one will suffice for an understanding of all.

The leg band illustrated in Figures 1 to 4, both inclusive, is provided with a transversely arranged, reinforcing strip, 20 which 35 is placed intermediate the ends of the leg band. The reinforcing strip 20 is provided with a plurality of reinforced eyelets 21, in parallel arrangement. The eyelets are arranged in this strip so that, when the leg band is placed in the desired position at the thigh portion, or the knee portion, of the pants leg, the reinforced eyelets, will be used in securing the leg band to the leg portion of the garment. In order to enable the 40 leg band to be attached to and held in place on the pants leg, the pants leg is constructed with the sets of reinforced eyelets 22 and 23, as shown in detail in Figure 5. The upper set of eyelets 22 is adapted for the positioning of the leg band to encircle the thigh portion of the garment, and the lower set of eyelets 23 is adapted to be used in positioning the leg band which may be used to encircle the knee portion of the garment. The 45 sets of eyelets 22 and 23 are placed in parallel rows and are, preferably, made in the outer sides of the leg portions of the garment adjacent the outer seams and they are placed substantially parallel with the seams.

When the eyelets 21 of the leg band are positioned adjacent the thigh portion of the garment the band may be laced to the garment by the lacing 24, which is threaded through the eyelets 21 in the leg band and 50 the eyelets 22 of the thigh portion of the

garment, thereby providing a means for securing the leg band to the outer, thigh portion of the leg of the garment. When it is desired to place a leg band on the knee portion of the garment, the eyelets 21 of the leg band are positioned adjacent the knee portion of the garment, and the leg band may be laced thereto by the aid of the lacing 25, which is threaded through the eyelets 21 in the leg band and the eyelets 23 provided in the knee portion of the garment, thereby providing a means for securing the leg band to the outer side of the knee portion of the garment. It will be apparent that the leg bands may be maintained and held in position in the sets of eyelets 22 and 23, so that the leg bands will not become unfastened or displaced during use by the player in the game. It will also be apparent that the leg bands are held and maintained against displacement while the opposite ends of the bands are being secured together on the legs or while they are being adjusted. When the foot-ball pants are not in use the leg bands may be held to them by the lacings 24 and 25 and thus the bands will not become lost or misplaced and are ready for use when desired. It will also be obvious that, according to the choice of the player, one or more of the leg bands may be removed from the garment.

The end of the leg band 26 is provided with a strip 27 which reinforces the end of the band. The strip 27 is supplied with a plurality of reinforced eyelets 28 arranged in parallel relation. The opposite end of the leg band 29 is supplied with a plurality of strips 30, 31, and 32 secured to the band and which serve to reinforce and strengthen it. A plurality of reinforced eyelets 33, 34 and 35 which are arranged in parallel relation to each other, are disposed in each of the reinforcing strips 30, 31, and 32. The eyelets 28 in the reinforcing strip 27 and the eyelets 33, 34, and 35 in the reinforcing strips 30, 31, and 32 are in substantial horizontal alignment with each other, and, therefore, when the leg band is wrapped around the leg of the wearer (the loose portions of material of the garment having been first 115 folded and arranged to suit the wearer, as indicated at *a*, *b*, and *c* in Figure 4) and the set or one row of the eyelets 28 are brought into register with one set, or row, of the eyelets 33, 34, or 35 in the opposite 120 end of the leg band, a lacing 36 may be threaded through the set or row of eyelets 28 and the set, or row, of eyelets chosen from among the three sets of eyelets at the opposite end of the leg band, and thereby 125 secure the ends of the leg band together. When the ends of the leg band have been drawn together tightly and secured with the lacing 36, all loose material of the leg portion of the garment will be held tightly 130

against the leg of the wearer and render this material inaccessible to the grasp of an opponent. The leg band, being drawn tightly against the leg of the wearer, will 5 present a smooth and even surface without wrinkles and without excess material of any sort which may be held by the opposing player.

It is manifest that the plurality of sets of 10 eyelets provided in the end 29 of the leg band will permit the opposite end of the leg band to be positioned with relation to each of these sets of eyelets or each of the individual rows of eyelets, so that a variation in 15 adjustment may be secured. It is also evident that, due to the flexibility and elasticity of the leg band, the degree of tightness desired by the wearer may be gained by adjusting the set or rows of eyelets 28 relatively 20 to the sets or rows of eyelets 33, 34, and 35 in the opposite end of the leg band. In Figures 1 and 4 two methods of treading the lacing 36 have been, respectively, shown. In Figure 1 it will be seen that the lacing 36 25 passes through the outer, single, transverse row of eyelets 28 and the inner, double, transverse rows of eyelets 35 of the leg band. In the figure the reinforced portion 27 is shown overlapping the reinforced portion 32, and only one of the rows of eyelets 35 30 in which the lace is threaded is exposed. In Figure 4 it will be seen that the lacing 36 passes through the outer, double, transverse 35 rows of eyelets 28 and the inner, double, transverse rows of eyelets 35 of the leg band.

In the modified arrangement illustrated in Figure 6 another form of structure for securing the legs of the garment and the leg band is illustrated. In this structure the 40 opposite ends of the leg band are, respectively, provided with a stud and socket arrangement which provides fastening means, such as is ordinarily referred to as a glove fastener. When the structure, as shown in 45 Figure 6 is employed, the studs 37 are arranged in parallel rows at one end of the leg band in a manner similar to the eyelets 33, 34, and 35 and are mounted in a plurality of reinforcing strips 38. The opposite end of 50 the leg band is provided with a reinforcing strip 39, to which the sockets 40 are secured. It will be understood that the leg band will be provided with eyelets intermediate its

ends so that the leg band may be laced to the outer sides of the garment, as illustrated 55 in Figure 1.

Another arrangement which may be used is illustrated in Figures 7 and 8. In this structure there is shown the straps 41 and 42 which may be employed to hold the leg 60 bands in position on the leg portion of the garment. When the straps 41 and 42 are used it would not be necessary to use the sets of eyelets 22 and 23 in the pants leg, as 65 shown in Figure 5. When this form of securing means is utilized it is not necessary to use a leg band embodying the rows of eyelets intermediate the ends of the leg band, such as the eyelets 21. When this form of structure is used each pants leg will be provided with a pair of the straps 41 and 42. The straps will be, respectively, arranged at the outer faces of the pants legs at the 70 thigh and knee portions. One of the ends of the leg band will be passed through the 75 loop formed by the strap and the opposite ends of the leg band will be secured together in a manner similar to that explained with reference to the construction illustrated in Figures 1 to 4, both inclusive, or as illustrated in Figure 6. Thus the leg band will be held in its proper position with respect to the garment and be capable of adjustment for the purpose and in the manner hereinbefore mentioned. 80

Having thus described the invention, what I desire to secure by Letters Patent is:

An elastic band adapted to be secured to a garment and encircle the limb of a person, 90 said band being arranged outside of the garment, said band having a reinforcing strip and parallel rows of eyelets in said strip to receive a lacing whereby the band may be laced to the garment, said reinforcing strip being disposed transversely of said band substantially midway of the ends of said band, 95 a series of parallel rows of eyelets at one end of the band, and a plurality of series of parallel rows of eyelets at the opposite end of the band, all of the rows of eyelets being arranged transversely of the band, the eyelets in the ends of the band permitting variations 100 of adjustment of said band.

In witness whereof, I hereunto subscribe my name this 11 day of January, A. D., 1923.

DAVID LEVINSON.
